UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

Application filed May 3, 1923. Serial No. 636,369.

To all whom it may concern:

Be it known that I, JOHN H. BARR, citizen of the United States, and resident of the borough of Manhattan, city of New York, in the county of New York, and State of New York, have invented certain new and useful Improvements in Typewriting Machines, of which the following is a specification.

10 My invention relates to bell ringing and line locking mechanism for typewriting machines and its principal object is to provide new and improved mechanism of the character stated. More specifically the object 15 of my invention is to simplify and improve the bell ringing and line locking mechanism disclosed in the patent to Barr and Barney #1,447,639, granted March 6, 1923.

The preferred form of my invention is 20 illustrated in the accompanying drawings, wherein

Figure 1 is a front-to-rear vertical sectional view of a typewriting machine embodying my invention, only so much of the machine 25 being shown as is necessary to a full understanding of said invention.

Figure 2 is a fragmentary plan view showing parts of the invention.

Figure 3 is a sectional view of a detail 30 drawn to an enlarged scale.

Figure 4 is a fragmentary vertical sectional view taken transversely through the upper part of the machine; and

Figures 5 and 6 are operating views.

35 As appears from Fig. 1, the main frame of the typewriting machine to which my invention is shown as applied comprises side plates 1 which are connected at the front by a U-shaped frame 2, the rear connection 40 comprising a cross plate (not shown). Mounted above the main frame is a traveling carriage comprising an inclined perforated plate 3 provided at its top and bottom with grooved bars 4. Fixed to the end portions 45 of the plate or bar 3, 4 are end plates 5. The grooved bars 4 provide seats or runways for sets of antifriction rollers 6, the upper set co-operating with a fixed track bar 7 secured to the upper end portion of an angular trough or bed plate 8 mounted on the frame plates 1. The bed plate 8 terminates forward in an upward extension formed with a grooved seat to provide a trackway that co-operates with the lower set of rollers 50 6. Journaled on the traveling element or

carriage 3—5 is a roller platen 10 with whose front face co-operate printing instrumentalities comprising type bars 11 which are normally supported on a rest member 12, said type bars each carrying two types. The 60 set of type bars are pivoted on a common pivot wire 13 mounted on a shiftable type bar support or segment 14. The heel of each type bar is formed with a cam slot 15 which is engaged by a pin 16 projecting from a bell crank 17 which is one of a set pivoted on a wire 18 mounted on the rest 12. Links 19 connect the bell cranks 17 with angular levers 20 pivoted at 21 in a sub-frame 22 which is detachably secured to the main 70 frame. Each lever 20 carries a pin 23 which engages in a slot 24 formed in the rear of a key lever 25, the set of key levers extending forward and being pivoted on fulcrum wires 26 in the sub-frame 22. Each 75 key lever has a key cap 27 which when depressed will operate through the described train of devices to swing the connected type bar into printing contact with the platen and the paper thereon. Mounted on the 80 carriage is a feed rack 28 intermeshing with a feed pinion 29 supported loosely on a horizontal shaft 30 having bearings on the bed plate 8. Fixed to said shaft is a toothed escapement wheel 31 which carries a pawl (not shown) that normally meshes with the feed pinion 29 so that feed movements from the traveling carriage will be transmitted through the rack 28 and pinion 29 to the 85 escapement wheel 31. The carriage is power driven, being connected to a spring drum 32 by a band 33 in such a way that the carriage is constantly urged leftward. 90

The escapement wheel 31 is adapted to control the carriage movements by escapement mechanism which need be only briefly described since preferably it is of the character disclosed in the patent to A. W. Smith No. 1,435,669, granted Nov. 14, 1922, said mechanism comprising three dogs mounted on a two-part rocker that is vibrated by the printing keys so that two of the dogs will co-operate with the escapement wheel to cause no-drop letter feeding movements of the carriage during return strokes of said printing keys, the third dog being operative by the space bar or key to cause a reverse or full-drop feed of the carriage. The dog rocker comprises a main part 34 and a secondary part 35 pivoted at 36 to the part 34. 100

105

110

Said dog rocker has stationary pivots 37 on which it is swung transversely of the escapement wheel 31. Rigid with the rocker part 34 is a holding dog 39 normally lying forward of the plane of the escapement wheel, the stepping dog 40 being normally engaged with said wheel, said dog 40 being pivoted on the rocker part 35. The third dog 43 is also pivoted to the rocker part 35 and has its tooth 43^a normally extending above the off-set portions of the teeth of the escapement wheel 31. The dogs 40 and 43 are loosely confined between the parts 34 and 35 and are adapted to swing bodily with 10 and on the part 35 about the center 36, all three dogs participating however in the swinging movements of the rocker on the pivots 37. The rocker is normally maintained in position by a spring 44 and is 15 adapted to be swung on its pivots 37 when the printing keys are actuated.

Movement is transmitted to the escapement mechanism from the type bars through contact faces 11^a thereon which 20 contact with the front face of a curved universal bar 45 housed in a depression 46 in the rear of the type bar segment 14. The universal bar 45 is part of a frame comprising rearward extensions 47 pivotally connected at 25 48 with crank arms 49 projecting upward from a shaft 50 which also has a rearwardly extending crank arm 51. Said universal bar frame further comprises an arm 52 which extends rearward from the bar 45 and carries a contact device 53 co-operative 30 with a contact screw 54 carried by the dog rocker, the construction being such that in both lower and upper case positions to which the universal bar shifts with the segment 35 14, the contact face 53 is adapted to engage with the screw 54. The arm 52 has a slotted lug 55 engaging a pin 56 on a crank arm 57 fixed to an axle 58 which also carries a crank arm 59 that is connected by 40 a link 60 with the crank arm 51, the construction assisting to synchronize movements of the universal bar frame as a whole. The pivotal supports 50 and 58 of said frame are mounted on a bracket member 61 to which the type bar segment 14 is secured, both elements being subject to case shifting movements. The universal bar frame is maintained in normal position by a spring 62. When one of the printing keys 27 is 45 actuated the associate type bar is swung to operative position, causing its contact face 11^a to act against the universal bar 45 and cause the contact device 53 acting against the screw 54 to operate the dog rocker 34, 50 35 and permit a letter space feeding movement of the carriage towards the left during the return movement of the dog rocker.

The escapement is also operative from the space bar or key 63 of the machine without 55 affecting the main rocker part 34. Said

space bar is mounted on arms 64 fixed to a rock shaft 65 from which a curved arm 66 extends rearward and terminates in a head 67 underlying the forward arm of a lever 68 having a pivot 69, the rearward arm of said lever being operative on a shouldered arm 71 pivotally supported on the carrier part 35. When the space bar is depressed, the arm 66 will be swung upward and the head 67 will actuate the lever 68 to cause its rear arm to press down on the shouldered arm 71 and swing the carrier part 35 on its pivot 36, thereby causing the stepping dog 40 to disengage from the escapement wheel and the third dog 43 to engage therewith. The construction is such that an escapement movement is thereby effected during the depression of the space bar.

The trains of bell ringing and line locking devices are operative in the present instance from one or more stationary contact devices or frame stops which are mounted on a rectangular stop bar 73 arranged above the top of the stationary track bar 7. The stop bar is provided at its under side with a series of teeth 74 and is carried by arms 75 which extend rearward and bear on stationary pivot pins 77 mounted on ears 78 projecting from the bar 7. The bar 73 may be thrown back by hand on the pivots 77 or may be lifted by key operated devices hereinafter described, to release the line lock. Adjustably supported on the bar 73 are stop or contact devices, one only of such devices being herein shown and numbered 79. Said device is preferably of the general construction of the contact devices disclosed in the aforesaid Patent No. 1,447,639, and 100 loosely embraces the bar 73, being formed with teeth which are spring pressed into engagement with the teeth 74. At its front side the device 79 is provided with a forwardly projecting lug or stop proper 80 having a straight vertical contact face 81 at its right-hand side and an inclined or cam face 82 at its under side. Said stop or contact 79—82 is adapted to co-operate with and actuate the bell ringing and line locking mechanism proper to which my present invention more particularly relates, and which will now be described. Secured to the middle portion of the upper carriage bar 4 at its front side as by screws 83 is a 110 detachable plate or bracket member 84 which is provided with projections or stop lugs 85 and 86. Pivoted to said bracket at 87 is an angular lever 88 which has an extension or stop portion 89. The lever 88 is mounted on the left-hand side of the bracket or support 84, and pivoted at 90 to said bracket at the right of the lever 88 is a second angular lever 91 which has a downwardly projecting extension 92 terminating in a curved end 93 that is adapted 115 120 125 130

to co-operate with the stopping portion 89 of the lever 88. An ear 94 projecting from the lever 91 above its pivot is forwardly bent and perforated to receive the 5 hook-like end of a draw spring 95, the opposite end of said spring being hooked over a pin 96 projecting from the lever 88 below its pivot 87. The draw spring connects the two levers and constantly tends to pull 10 the upper arm of lever 91 towards the lower arm of lever 88. Said spring normally maintains the two levers in the position shown in Fig. 4, the upper arm of the lever 88 contacting with the stop 85 and the upper arm 15 of the lever 91 contacting with the stop 86.

Both levers 88 and 91 are adapted to be actuated or turned on their pivots by the contact 79—82, the lever 88 being first 20 actuated to operate the bell ringer or striker and the lever 91 being subsequently actuated to lock the line of writing. The two levers operate on the same element or member successively, their effect being to move said 25 element or member oppositely. In the present instance the oppositely actuated element is a third lever or connector 97 which is bent at about midway of its length and is pivotally connected at its end portions 30 with the lower arms of the levers 88 and 91. The pivotal connection 98 with the lever 91 is a plain pivot, but in order to allow freedom of motion the left-hand end portion of the lever or link 97 is slotted as indicated at 99 to co-operate with a headed pin or pivot 100 projecting from the lower arm of the lever 88, thus providing a loose 35 pivotal connection. Pivoted at 101 at the bend of the lever 97 is a roller or wheel 102 which runs in a channel bar or trough-like member 103. Said member extends lengthwise of the carriage behind the bar 3, 4 but has a stationary mounting so that as the carriage travels the roller 102 runs 40 in the channel bar, the construction providing that the roller may act on or communicate movement to the channel bar at any point in the carriage travel. The channel bar 103 is pivotally connected at 104 near its ends to the horizontally disposed arms of angular levers or bell cranks 105. These bell cranks as most clearly appears 45 in Fig. 3 are pivotally supported on shoulder screws 106 which are threaded into bosses or lugs 107 projecting forward from the front vertical face of the bed plate or trough 8. The downwardly extending arms of the bell cranks 105 carry shouldered 50 pivot pins 109 which provide pivotal supports for the end portions of a second bar 110, said bar being arranged below and parallel with the channel bar 103. It will be observed that the bell cranks 105 perform the dual functions of supporting both 55 bars 103 and 110 and also of providing 60 connections between the two bars whereby motion may be transmitted from one to the other. Further, the bell cranks 105 and the bar 110 connecting them insure parallel movement of the bar 103. As 70 hereinafter explained the roller 102 is adapted to move the channel bar 103 in opposite directions from its normal position or up and down, and it will be apparent that the up and down or transverse movements of the bar 103 will be so transmitted by the bell cranks 105 to the bar 110 that said bar 110 will be oppositely moved in a direction lengthwise of itself 75 from its normal position.

The bar 110 is provided with oppositely facing lugs 111 and 112, the lug 111 operating whenever the bar is moved longitudinally rightward to actuate the bell ringer, while the lug 112 is adapted to operate the 80 line lock devices during a subsequent movement of the bar 110 in the opposite direction or towards the left. The lug 111 is adapted to engage with a pin 113 projecting forward from the upper end portion of 85 an arm 114 which is suspended from a screw pivot 115 fixed to the front of the vertical portion of the bed plate 8 near its right-hand end, the arm 114 projecting downward through an opening 8^a in the bottom of the 90 bed plate, said arm at its lower end carrying a head 116. This head projects backward from the arm and lies inside the rim of a bell 117 which is secured at 118 to a bracket or arm 119 that is fixed at its upper end by 95 screws 120 to the rear face of the vertical part of the bed plate 8. Said arm 119 is off-set as indicated at 119^a to carry it outside the rim of the bell. The bell ringer or 100 hammer 114, 116 is spring pressed, a draw 105 spring 121 being hooked over the pin 113 at one end, the opposite end of said draw spring being anchored to a pin 122 projecting from the bed plate 8. The pin 122 also acts as a stop for the bell ringer or striker, 110 serving to maintain the left-hand face of a projection 114^a from the arm 114 normally in contact with the pin 122 as shown in Fig. 4. It will be apparent that when bar 110 is moved longitudinally rightward the lug 111 acting against the pin 113 will swing the arm 114 rightward on its pivot 115, stretching the spring 121 and carrying the head 116 away from the rim of the bell 117; and that on suddenly releasing the bar 110 115 the spring 121 will become effective to swing or throw the arm 114 rapidly rightward and cause the head 116 to strike the rim and ring the bell.

When the bar 110 is actuated longitudinally towards the left the lug or projection 112 will actuate the line locking train, said train comprising a yoke piece or angular lever member 123 which is composed of a vertical portion 124 having parallel ears 125 120

130

and 126 bent horizontally forward from its top and bottom, and further comprises an off-set downwardly curved portion 127. The ears 125 and 126 are perforated to receive a pivot pin or bearing 128 which is vertically disposed and is secured at its ends in the top and bottom ears 129 and 130 of an angular bracket member which further comprises a vertical portion 131 and a horizontal portion 132. The top ear 129 is bent off from the top of said vertical portion and the bottom ear 130 is off-set leftward from the rear of said horizontal portion. At its front end said horizontal portion 132 terminates in a downwardly bent ear 133. The bracket comprising the parts numbered from 129 to 133 is supported on the bed plate 8 being arranged so that the portion 131 is secured to the vertical front face of said bed plate by a screw 134, the lower portion of said bracket passing through an opening in the bed plate and its bottom part 132 being secured to the under face of the bed plate by a screw 135. The bracket ears 129 and 130 loosely embrace the ears 125 and 126 of the member 123 so that said member may turn on the pivot pin 128 as a center when moved by reason of the pressure of the lug 112 against the ear 125 projecting forward across the path of the lug 112. The turning of the member 123 on its pivot through the action of the lug 112 is effective to swing the arm or extension 127 forward about the pivotal axis 128. This arm is perforated to receive the rear end of a slide rod 136 said slide rod passing at its forward end through and bearing in a hole in the ear 133. The slide rod is flattened, at 137, forward of the extension 127 so that said extension engaging with the rear end of the flattened portion may slide the rod 136 forward and against the pressure of a wire spring 138 coiled around the forward portion of the rod and confined between the ear 133 and the front end of the flattened portion 137.

The front end of the rod 136 is adapted to actuate a train of line locking devices which may and preferably does correspond with a train of mechanism disclosed in the aforesaid patent to Barr & Barney No. 1,447,639. Said train need but be briefly described herein, reference being had to the patent for a fuller and more complete disclosure. As shown in Figs. 1 and 2 herein, said train includes a one-piece controlling member or stop preventer 139 comprising an upright arm 140 rising from a horizontal cross portion 141 which terminates in forwardly bent ears 142. Curving forward from the cross portion 141 is a finger 143 having a side lug 144. The ears 142 are perforated to bear on a rod 145 which is supported on a U-shaped bracket comprising a cross bar 146 and parallel arms 147

which terminate in ears 148 that receive headed screws 149 threaded into the member 61, the side arms 147 having bearing openings which receive the rod 145. The cross bar 146 has an upward extension 150 which acts as a stop for the member 139. The rear portion of said member is maintained in contact with the stop 150 by a coiled spring 151 anchored at its front end to a pin 152 projecting from the right-hand arm 147, the rear end of said spring being hooked through a hole in the lug 144. When thus maintained in normal position the finger 143 sustains in inoperative position a pivoted gravity-operated stop 153 for the universal bar. Said stop is in the form of a U-shaped sheet metal frame comprising a cross portion 154 and downwardly extending sides 155 which loosely embrace the bracket arms 147 and are perforated to bear on the rod or shaft 145, the ends of said shaft being spread to prevent displacement. An extension 156 from the body portion 154 provides a stop proper, the forward edge of which is adapted to co-operate with a lug 157 projecting upward from the arm 52 of the universal bar frame. Said abutment is normally maintained up out of the path of said lug but when released by the controlling frame 139 drops down through the force of gravity close behind the lug 157 so as substantially to prevent movement thereof. It will be understood that when the slide or rod 136, 137 is pressed forward by the arm 127, said slide acting against the arm 140 of the member 139 will swing said member and cause the finger 143 to release the stop member 153 so that the stop 156 may block the stop 157, locking the line by preventing operation of the universal bar and the type bars. The controlling frame 139 also controls the operation of a gravity-operated stop device or member 158 for the space bar mechanism, which member comprises a cross portion terminating in pintles 159 and having a downwardly extending finger 160 and an extension 161 which is arranged behind and is controlled by the finger or arm 140. Normally the finger 160 lies behind and out of the path of a stop face 68^a on the lever 68 but when the controlling member 139 is rendered inoperative as described, it permits the arm 160 to swing forward on pintles 159 until it overlies the stop face 68^a, thus preventing operation of the lever 68 from the space bar frame thereby locking said space bar from operation.

Line locking release mechanism is provided which is preferably of the character disclosed in the aforesaid Patent #1,447,639, said mechanism which is completely disclosed in said patent, comprising a finger 162 fixed to and projecting rearward from the toothed stop bar 73 near the

left-hand end thereof. Said finger is controlled by a lever 163 pivoted to the bed plate 8 at 164 and provided at its upper arm with a cam slot for actuating the finger 162, the lower arm of said lever likewise being formed with a cam slot which is engaged by an actuating pin (not shown) on a pivoted plate 165 which is adapted to be swung up by a slide rod 166 pivoted at its lower end to a lever 167 arranged in the base of the machine and provided at its front end with a key 168. On depressing said key 168 the slide rod 166 is raised, swinging up the plate 165 and actuating the lever 163, causing it in turn to cam up the finger 162 and raise the stop bar and the stops thereon about the pivotal axis 77, so that said stops or contacts will clear the co-operating traveling contacts on the carriage.

Referring now briefly to the operation of the line lock mechanism, and assuming that the carriage has traveled leftward to a point where the upper arm of the traveling contact or lever 88 will contact with the stop face 81 as shown in Fig. 4, it will be understood that further movement of the carriage towards the left will cause the lever 88 not only to travel bodily with the carriage but also to swing pivotally on its fulcrum or pivot 87, the upper arm swinging towards the right and the lower arm upward and leftward until said lever assumes the position shown in Fig. 5. As the lower arm of the lever swings upward the pin 100 acting against the slotted left-hand end of the lever or connector 97 will swing said slotted end upward, the lever turning on the center 98 which will act as a fulcrum and will remain fixed by reason of the co-operation between the stops or preventive means 89 and 93. The preventive action of these stops or interlocking devices will be best understood by a comparison of Figs. 4 and 5. In Fig. 4 it will be seen that the ends of the stop devices are clear of each other so that either lever 88 or 91 is free to move on its fulcrum or center away from its limiting stop lug. As, however, the lever 88 begins to turn on its fulcrum 87 the stop 89 will swing leftward over the stop 93, thus preventing any lifting movement of said stop, and consequently of the lever 91 of which it is a part. It may here be noted that the cam faces of the stops or interlocking devices 89 and 93 are curved in conformity with each other so as to permit relative crosswise movement of the parts, although these curved faces remain quite close together. As a result of the leftward movement of the stop 89 to the Fig. 5 position and the consequent locking of the lever 91, the pivot 98 will be prevented from moving in one direction by the coacting stops 89 and 93 and from movement in the other direction by

stop 86. The lever 97 thus swings up on a fixed axis 98 at its right-hand end, and so will lift the roller 102, raise the channel bar 103 and move the connected bar 110 longitudinally rightward, moving the bell striker 70 or hammer away from the bell, as has been described. This movement will continue until the parts reach the position shown in Fig. 5. As leftward stepping movement of the carriage continues, however, the lever 75 88 will clear the lug or contact 80, permitting the bell ringing train to be restored to normal position by the springs 95 and 121, causing the bell to ring and thus notifying the operator of the approach of the end of 80 the line. Further leftward travel of the carriage will bring the lever 91 into contact with the stop face 81 and will swing said lever on its fulcrum or axis 90 to the position shown in Fig. 6. This swinging move- 85 ment of the lever will cause a downward swinging movement of the lever 97 which this time will turn on the pin 100 as a center or fulcrum. Said pin will be held fixed by reason of the coaction of the stops, 93 90 and 89, the stop 93 being swung up to the left of the stop 89, thus preventing leftward movement of said stop 89 about the center 87 and consequently fixing the lever 88 of which said stop 89 is a part since said lever 95 cannot turn on its axis in either direction, movement in one direction being prevented by the coacting stops or interlocking devices 93 and 89 and movement in the other direction being prevented by the stop 85. 100 Consequently, as has been stated, the lever 97 will swing downward in the opposite direction from its bell ringing movement and about a different center or fulcrum, this movement of the lever or connector 97 carrying downward with it the roller 102 and causing the channel bar 103 to move in the opposite direction from its normal position or transversely downward. The downward movement of the channel bar will be 105 transmitted through the bell cranks 105 to the bar 110 which will likewise be oppositely moved from its normal position or longitudinally leftward, causing the lug 112 acting on the extension or arm 127 to swing 110 the member 123 on its axis 128, the arm 127 of said member being thereby swung forward to push the slide or rod 136, 137 forward to actuate the universal bar stop and the space bar stop as has heretofore been de- 115 scribed. It will further be observed that not only are the type bars and the space bar locked against actuation but the carriage of the machine is also arrested or limited by reason of the engagement of the stop 91 120 with the stationary or frame stop, 80 as shown in Fig. 6. It will be seen that the co-operating stops or interlocks on the levers 88 and 91 prevent improper operation of the mechanism, as 125 130

without said stops the third lever or connector 97 might fulcrum on the roller 102, instead of, as desired, at one or the other of its own ends, and as a result, would merely cause one of the levers 88 and 91 to move the other without affecting the channel bar 103.

To release the line lock and the carriage in order to permit the addition of one or more characters as is sometimes desired, it is only necessary to depress the release key 168 thus causing the stop bar 73 to be swung upward as has been described and thereby raising the stop 80 to clear the path of the carriage stop or lever 91. During return movements of the carriage the upper ends of the levers 91 and 88 will successively engage with the inclined or cam face 82 to cam up stop 79 and the stop bar 73 so as to permit the unobstructed rightward movement of the carriage to continue. It has not been thought necessary to show the final line stop on the stop bar 73, nor the margin stop or stops on said bar for limiting the return movements of the carriage.

It will be noted that by my invention there is provided in combination with a traveling carriage, printing instrumentalities and a contact device or stop, line lock and bell ringing mechanism operative by said contact device and including an element movable in opposite directions from a single normal position, movement of such element in one direction actuating the bell striker and movement in the other direction actuating the line lock devices to lock the line; that in the present instance said contact device or stop is mounted on the stationary part or frame of the machine while the directly co-operating parts of the bell ringing and line lock mechanism are mounted on the traveling element or carriage; that the oppositely movable element is in the present instance a bar which is movable transversely of itself or up and down by a lever having a changing fulcrum, the upward movement actuating the bell striker or ringer and the downward or opposite movement locking the line; that there is also provided a second bar which is also oppositely movable from a single normal position, said second bar being, however, movable longitudinally of itself instead of transversely, this longitudinal movement being affected by the connections between the two bars, said connections comprising a pair of bell cranks: that said connections or bell cranks not only connect the two elements or bars but also provide supports therefor, the first or transversely movable bar being pivotally supported on the horizontally disposed arms of the bell cranks while the longitudinal movable bar is pivoted on the vertical arms of the bell cranks, the construction being such that the transverse movements com-

municated to the first bar cause or effect the longitudinal movements of the second bar; that said second bar is provided with a pair of projections or lugs, one for the bell ringing train of connections and the other for the line lock train; that the bell ringing and line lock mechanisms comprise two connected levers which are successively operative or movable on their fulcrums by a contact device, means being provided for preventing operation of more than one of said levers at a time; that said means comprise devices or stops, one on each lever, for preventing individual movement of the other lever, the preventive stops functioning during the entire period of movement of the actuated lever, the construction being such that the levers are adapted to interlock so as to prevent simultaneous movement; that the said levers are connected by spring means, in the present instance, a draw spring, that said levers are further connected by an element, connector, or third lever which is associated with means which prevent it from transmitting movement from one of the first two levers to the other, while permitting said third lever to transmit movement from both the first two levers to the two connected bars above mentioned, the third lever having two fulcrums alternatively employed.

Various changes may be made without departing from my invention.

What I claim as new and desire to secure by Letters Patent is:—

1. In a typewriting machine, the combination of a traveling carriage, printing instrumentalities, a contact device, and line lock and bell ringing mechanism operative thereby including an element movable in different directions from a single normal position, movement in one direction actuating the bell striker and movement in the other direction locking the line.

2. In a typewriting machine, the combination of a traveling carriage, printing instrumentalities, a contact device, and line lock and bell ringing mechanism operative thereby including a bar movable transversely in opposite directions from a central normal position, movement of the bar in one direction actuating the bell ringer and movement in the other direction locking the line.

3. In a typewriting machine, the combination of a traveling carriage, printing instrumentalities, a contact device, and line lock and bell ringing mechanism operative thereby including two bars both oppositely movable from normal positions, movement in one direction operating the bell ringer and movement in the opposite direction operating the line lock.

4. In a typewriting machine, the combination of a traveling carriage, printing instrumentalities, a contact device, and line

lock and bell ringing mechanism operative thereby including two bars and connections between them whereby the transverse movement of one bar effects a longitudinal movement of the second bar.

5. In a typewriting machine, the combination of a traveling carriage, printing instrumentalities, a contact device and line lock and bell ringing mechanism operative thereby including two bars and connections between them whereby the transverse movement of one bar effects a longitudinal movement of the second bar, said second bar moving in one direction from normal position to actuate the bell striker and moving in the opposite direction from normal position to lock the line.

6. In a typewriting machine, the combination of a traveling carriage, printing instrumentalities, a contact device, and line lock and bell ringing mechanism operative thereby including two bars and connections between them whereby the transverse movement of one bar effects a longitudinal movement of the second bar, said second bar being provided with a pair of lugs, one lug to actuate the bell ringer and the other to lock the line.

7. In a typewriting machine, the combination of a traveling carriage, printing instrumentalities, a contact device, and line lock and bell ringing mechanism operative thereby including two bars and connections between them whereby the transverse movement of one bar effects a longitudinal movement of the second bar, said connections also serving as supports for both of the bars.

8. In a typewriting machine, the combination of a traveling carriage, printing instrumentalities, a contact device, and line lock and bell ringing mechanism operative thereby including two bars and connections between them whereby the transverse movement of one bar effects a longitudinal movement of the second bar, said connections between the two bars comprising bell cranks which serve both to transmit movement from one bar to the other and also to support the two bars.

9. In a typewriting machine, the combination of a traveling carriage, printing instrumentalities, a contact device, and line lock and bell ringing mechanism operative thereby including a bar, a pair of bell cranks, each having a horizontally disposed arm and a vertically disposed arm, said bar being pivotally supported by the horizontal arms of said bell cranks, a second bar pivotally supported by the vertical arms of said bell cranks, a bell striker operative by said second bar, and a line lock stop also operative by said second bar.

10. In a typewriting machine, the combination of a traveling carriage, printing in-

strumentalities, a universal bar, escapement devices, a contact device, two co-operating contact devices, a channel bar, a connector between said bar and two of said contact devices, a roller on said connector engaging in 70 said channel bar, a bell striker operative from said channel bar, and a line lock stop operative from said channel bar.

11. In a typewriting machine, the combination of a traveling carriage, printing instrumentalities, a contact device, and line lock and bell ringing mechanism operative thereby including two bars, connections between them whereby the transverse movement of one bar effects a longitudinal movement of the second bar, a pair of lugs on said second bar, a spring pressed striker operative by one lug, a bell with which said striker coacts, and line lock devices operative by the other of said lugs.

12. In a typewriting machine, the combination of a traveling carriage, printing instrumentalities, a contact device, and line lock and bell ringing mechanism operative thereby including two connected bars, one 90 provided with lugs, a spring pressed bell striker operative by one of said lugs, a bell crank operative by the other of said lugs, a spring pressed slide, and a line lock stop controlled from said slide.

13. In a typewriting machine, the combination of a traveling carriage, printing instrumentalities, a universal bar operative thereby, a space bar, escapement devices operative by said universal bar and said space 100 bar, a contact device, and line lock and bell ringing mechanism operative thereby including two bars, connections between them whereby the transverse movement of one bar effects a longitudinal movement of the 105 second bar, a pair of lugs on said second bar, a spring pressed striker operative by one lug, a bell with which said striker coacts, a bell crank operative by the second of said lugs, a spring pressed slide actuated 110 by said bell crank, a universal bar stop controlled by said slide, and a space bar stop also controlled by said slide.

14. In a typewriting machine, the combination of a traveling carriage, printing instrumentalities, a universal bar operative thereby, a space bar, escapement devices operative by said universal bar and said space bar, a contact device, two bars, connections between them whereby the transverse movement of one bar effects a longitudinal movement of the second bar, a pair of lugs on said second bar, a spring pressed bell striker operative by one lug, a bell crank operative by the second of said lugs, 120 a spring pressed slide actuated by said crank, a pivoted member operated by said slide, and a pivoted stop for said universal bar controlled by said pivoted member.

15. In a typewriting machine, the combi- 130

nation of a traveling carriage, printing instrumentalities, a universal bar operative thereby, a space bar, escapement devices operative by said universal bar and said space bar, a contact device, two bars, connections between them whereby the transverse movement of one bar effects a longitudinal movement of the second bar, a pair of lugs on said second bar, a spring pressed bell striker operative by one lug, a bell crank operative by the second of said lugs, a spring pressed slide actuated by said crank, a pivoted member operated by said slide, a pivoted stop for said universal bar, and a pivoted stop for said space bar, both of said stops being controlled by said pivoted member.

16. In a typewriting machine, the combination of a traveling carriage, printing instrumentalities, a stationary contact device mounted on the frame of the machine, two contact devices mounted on the traveling carriage, a bar movable in opposite directions by the successive coaction of said carriage carried contact devices with said stationary contact device, a bell striker operative by said bar when it moves in one direction, and a line lock stop operative by said bar when it moves in the opposite direction.

17. In a typewriting machine, the combination of a traveling carriage, printing instrumentalities, a contact device, two contact devices co-operating therewith, an element movable in one direction by the co-action of one of said co-operating devices with said first named contact device, said element being movable oppositely by the co-action of the second of said contact devices with said first named contact device, a bell striker operative by said element, and a line lock stop also operative by said element.

18. In a typewriting machine, the combination of a traveling carriage, printing instrumentalities, a contact device, and line lock and bell ringing mechanism comprising two connected contact devices successively co-operative with and movable by said first named contact device, and devices for preventing movement of one of said connected contact devices after movement of the other of said connected contact devices has started.

19. In a typewriting machine, the combination of a traveling carriage, printing instrumentalities, a contact device, and line lock and bell ringing mechanism comprising two connected levers successively operative by said contact device, and means for preventing operation of more than one of said levers at a time.

20. In a typewriting machine, the combination of a traveling carriage, printing instrumentalities, a contact device, line lock and bell ringing mechanism comprising two connected levers successively operative by

said contact device, and devices one on each lever for preventing movement of the other lever.

21. In a typewriting machine, the combination of a traveling carriage, printing instrumentalities, a contact, bell ringing devices comprising a lever operative by said contact, line locking devices comprising a second lever also operative by said contact, and means for preventing movement of one lever while the other lever is being moved.

22. In a typewriting machine, the combination of a traveling carriage, printing instrumentalities, a contact, bell ringing devices comprising a lever operative by said contact, line locking devices comprising a second lever also operative by said contact, and spring means connecting said levers, said levers being adapted to interlock when one of them is moved so as to prevent movement of the other.

23. In a typewriting machine, the combination of a traveling carriage, printing instrumentalities, a contact, bell ringing devices comprising a lever operative by said contact, line locking devices comprising a second lever also operative by said contact, connections between said levers, and coacting stops on said levers.

24. In a typewriting machine, the combination of a traveling carriage, printing instrumentalities, a contact, bell ringing devices comprising a lever operative by said contact, line locking devices comprising a second lever also operative by said contact, spring means acting on said levers, stops against which said levers are normally maintained by said spring means, mechanical connections between said levers, and stops on said levers adapted to coact with each other to prevent movement of more than one lever at a time.

25. In a typewriting machine, the combination of a traveling carriage, printing instrumentalities, a contact, bell ringing devices comprising a lever operative by said contact, line locking devices comprising a second lever also operative by said contact, a spring connecting said levers, stops against which said levers are normally maintained by said spring, a link connecting said two levers, and projections on said levers adapted to coact with each other to prevent movement by said contact of more than one of said levers at a time.

26. In a typewriting machine, the combination of a traveling carriage, printing instrumentalities, a contact, bell ringing devices comprising a lever operative by said contact, line locking devices comprising a second lever also operative by said contact, spring means acting on said levers, stops against which said levers are normally maintained by said spring means, a connector connecting said two levers, and means inde-

pendent of said connector for preventing it from transmitting movement from one of said levers to the other.

27. In a typewriting machine, the combination of a traveling carriage, printing instrumentalities, a contact, bell ringing devices comprising a lever operative by said contact, line locking devices comprising a second lever also operative by said contact, 5 spring means connecting said levers, stops against which said levers are normally maintained by said spring means, a connector pivoted to an arm of one of said levers and also having a pin and slot connection with 10 an arm of the other of said levers, and means for preventing said connector from transmitting movement from one of said levers to the other.

28. In a typewriting machine, the combination of a traveling carriage, printing instrumentalities, a contact, bell ringing devices comprising a lever operative by said contact, line locking devices comprising a second lever also operative by said contact, 20 spring means acting on said levers, stops against which said levers are normally maintained by said spring means, a connector between said two levers, and a bar oppositely movable by said connector, movement of said 25 bar in one direction being effective to ring the bell and movement in the opposite direction operating to lock the line.

29. In a typewriting machine, the combination of a traveling carriage, a contact 35 thereon, printing instrumentalities, a universal bar operative thereby, two levers pivoted on said carriage and successively operative by said contact, a connector between said levers and successively operated 40 by each of them, a bar oppositely movable by said connector under successive operations thereof, a bell-ringing device connected to said bar and a line locking device connected to said bar and effective to lock said universal bar.

30. In a typewriting machine, the combination of a traveling carriage, a contact thereon, printing instrumentalities, a universal bar operative thereby, two levers 50 pivoted on said carriage and successively operative by said contact device, a connector connecting said levers and operated by them successively, a bar oppositely movable by said connector under successive operations thereof, a second bar oppositely movable by the first named bar, a bell ringing device on said second bar and a line locking device 55 also on said second bar.

31. In a typewriting machine, the combination of a traveling carriage, printing instrumentalities, a contact on the frame of the machine, a pair of spring pressed levers mounted on the carriage and successively co-operative with said contact during 60 the carriage travel, stops on said carriage

with which said levers are normally in contact, a connector between said levers, stops on said levers for preventing said connector from transmitting movement from one lever to the other, and a bell ringing and line locking bar oppositely movable by said connector. 70

32. In a typewriting machine, the combination of a traveling carriage, printing instrumentalities, a universal bar, escapement devices, a contact device, two co-operating contact devices, a lever member between said two co-operating contact devices and pivotally connected at its end portions with said two devices, a channel bar, a roller on said lever member engaging in said channel bar, means for varying the fulcrum of said lever member from one pivotal connection to the other to cause said roller to move the channel bar oppositely, a bell striker operative from said channel bar, and a line lock stop also operative from said channel bar. 75 80

33. In a typewriting machine, the combination of a traveling carriage, printing instrumentalities, a contact, bell ringing devices comprising a lever operative by said contact, line locking devices comprising a second lever also operative by said contact, said levers successively co-operating with said contact, a third lever pivotally connected at its end portions to said first and second levers, and means for causing said first and second levers to effectively actuate said third lever in alternation to move it oppositely. 90 95

34. In line lock and bell ringing mechanism for typewriting machines, the combination of a lever for causing the bell to ring, a lever effecting the locking of the line, and a third lever having connections with both of said first two levers and being movable in opposite direction by them. 100 105

35. In line lock and bell ringing mechanism for typewriting machines, the combination of a train of three levers, the intermediate lever of the train being pivoted to both of the others and being movable first by one of the other levers in one direction and next by the other of said other levers in the opposite direction. 110 115

36. In line lock and bell ringing mechanism for typewriting machines, the combination of three levers, two of said levers carrying the third lever, and means for fixing first one and then the other of the two carrying levers so that turning movement on their fulcrums in either direction is prevented. 120

37. In line lock and bell ringing mechanism for typewriting machines, the combination of three levers, two of said levers carrying the third lever, and means for fixing first one and then the other of the two carrying levers so that turning movement on their fulcrums in either direction is pre- 125 130

vented, said means being rendered effective by the carrying levers themselves.

38. In line lock and bell ringing mechanism for typewriting machines, the combination of three levers, two of said levers carrying the third lever, and stop devices for preventing the two carrying levers from rotating on their fulcrums in either direction, certain of said stop devices being relatively stationary and the others of said stop devices being on the carrying members themselves.

39. In line lock and bell ringing mechanism for typewriting machines, the combination of three levers, two of said levers carrying the third lever, stop devices for preventing the two carrying levers from rotating on their fulcrums in either direction, certain of said stop devices being relatively stationary and the others of said stop devices being on the carrying members themselves, and spring means for normally maintaining said two carrying levers in contact with said relatively stationary stops.

40. In line lock and bell ringing mechanism for typewriting machines, the combination of two spring pressed levers, a third

lever pivotally connected at its ends to said spring pressed levers, a bar having a varying engagement with said third lever, and means for causing said third lever to fulcrum alternately on its two pivotal connections to actuate said bar.

41. In a typewriting machine, the combination of a key operated universal bar, a stationary contact device, a traveling carriage, a bracket detachably secured to said carriage, two levers fulcrumed on said bracket and successively operative by said stationary contact during the travel of the carriage, a third lever carried by said first named levers, a bell ringer on the frame of the machine operative by said third lever, and a stop for the universal bar on the frame of the machine, said stop being also operative by said third lever.

Signed at the borough of Manhattan, city of New York, in the county of New York and State of New York this 30th day of April, A. D. 1923.
